INVENTOR

UNITED STATES PATENT OFFICE.

GEORGE HENRY ELWELL, OF CLEVELAND, OHIO, ASSIGNOR TO CARR FASTENER COMPANY, OF CAMBRIDGE, MASSACHUSETTS, A CORPORATION OF MAINE.

SNAP FASTENER.

Application filed January 3, 1922. Serial No. 526,862.

To all whom it may concern:

Be it known that I, GEORGE HENRY ELWELL, a citizen of the United States, residing at Cleveland, in the county of Cuyahoga and State of Ohio, have invented certain new and useful Improvements in Snap Fasteners, of which the following is a specification.

My invention relates to snap fasteners.

10 The object of my invention is to provide a positive fastening means for the temporary fastening together of fabric to fabric or to a rigid object; and to provide such a fastening device the members of which are 15 easily snapped together with a single manual movement, and also separated without necessarily tipping either member.

With this and other objects in view, as will more fully hereinafter appear, the invention consists in certain novel features of construction and arrangement of parts hereinafter described, illustrated in the accompanying drawing and particularly pointed out wherein patentable novelty is claimed 25 for certain features of the device, it being understood that within the scope of what hereinafter thus is claimed various changes in form, proportion, size and minor details of the construction can be made without departing from the spirit or modifying any of the advantages of the invention.

The following is the description of an embodiment of my invention reference being had to the accompanying drawing in 35 which Figure 1 is a cross-sectional view of the separated members of the device, with push button element shown in full; Figure 2 is a similar cross-sectional view showing interlocked members; Figure 3 is a similar 40 cross-sectional view showing members in proper position for either interlocking or separation; Figure 4 is a detail view of interior of button member; Figure 5 is a detail view of a button member part; and Figure 45 6 is a face view of interlocked members.

Referring more particularly to the drawing in which similar numbers refer to similar parts:—

50 This snap fastener is comprised of a button element 1 and a shank element 2, as distinctly shown in Figure 1. The button element resembles, in a general way, the well known snap button having a face 3, attaching means 4, shank passage 5 extending en-

tirely through the button element, as shown 55 in Figures 1, 2, and 3, and resilient arms 6 normally resting in said passage 5, as shown in Figure 4, said arms being adapted to be engaged by the shank element 2, as it enters said passage 5, and become interlocked therewith, as shown in Figure 2. I provide this button element, however, with back plate 7 having bur 8 entirely surrounding said passage 5, as shown in Figures 1, 2, 3, and 5. Clamp plate 9 is provided as 60 the usual method of protecting the under side of the fabric to which the button is attached by means of clamps 4. The shank element 2 has a tubular shank post 10 and attaching base 11, as shown in Figures 1, 2, and 3. This attaching base may be provided with any of the well known means adapted to attach said element 2 to fabric or to any rigid object. Within said tubular shank post 10 is mounted push button 12. 70 This push button 12 in form resembles a shank post 13 having a head 14 the exterior surface of which is rounded and the greatest diameter of said head 14 being no greater than the outside diameter of the free 80 extremity of said tubular shank post 10, as shown in Figures 1, 2, and 3. Said shank post 13 is slidably mounted within said tubular shank post 10, the rear end 15 of said shank post 13 being subjected to a blow, 85 after assembling, sufficiently heavy to increase the diameter of its extremity, as shown in Figures 1, 2, and 3, and thus providing a positive check to the forward movement of said push button 12, as shown 90 in Figures 1 and 2. Said head 14 is provided with an under-surface 16 lying in a plane which is at right angles with the surface of said shank post 13, and the exterior wall of the free extremity 17 of said 95 tubular shank post 10, as distinctly shown in Figure 1, is rounded off to provide a shallow groove 18 surrounding the shank element 2 when surface 16 of said head 14 is in close relation to said extremity 17, as shown in Figure 3, the base of said groove 18 being declined toward said under-surface 100 16 of said head 14. When, however, the push button 12 is in its most forwardly position, as shown in Figures 1 and 2, a slot 19 is thereby formed surrounding the shank element 2 between said undersurface 16 and said extremity 17, as distinctly

shown in Figure 1, the base of said slot 19 being provided by the surface of shank post 13 of push button 12.

In operation, the button element in being snapped onto the tubular shank post 10 engages the resilient arms 6 with rounded head 14 of push button 12 and, with slight pressure on the button element said push button is made to assume its most rearwardly position and said arms 6 to yield against their spring tension sufficiently to pass said head 14 and temporarily lodge in groove 18, as shown in Figure 3. Immediately and automatically the spring tension of said arms 6 having a strong tendency to restore said arms 6 laterally to their normal position causes said arms 6 to slide off said declined base of said groove 18 and, no resistance being offered by the under-surface 16 of head 14, the sliding movement of said arms 6 operates push button 12 to its most forwardly position as said arms 6 force their way into slot 19, as shown in Figure 2. With tubular shank post 10 lodged within bur 8 of back plate 7, and arms 6 lodged tightly within slot 19, said button and said shank members are thereby positively interlocked against withdrawal, one from the other, either by direct pulling or by tipping one member upon the other. To separate said members the rounded head 14 of push button 12 which, when the members are interlocked, slightly projects through the face plate 3 of the button element, as shown in Figures 2 and 3, is pushed inwardly and, while the members can then be separated by direct withdrawal, it is more natural and, perhaps, more easy to simultaneously, and with the same hand, push inwardly said push button 12 and to pull outwardly the curtain, to which said button is attached, just below said button element. This action forces arms 6 from slot 19 into groove 18, as shown in Figure 3, from which position arms 6 can be easily forced over said head 14 by a direct pull of the button element or in the manner above described. While this manner of disengaging the members of a snap button is usually well understood, as when a rigid shank head slightly projects entirely through the button element and the thumb is placed upon the rigid head to secure proper purchase upon the lifting of the button element, yet to facilitate a definite understanding as to the manner of disengagement of the members of this snap fastener I have provided that upon the exterior surface of said face plate 3 shall appear, if desired, the words "Push" and "Pull," an arrow connecting the first word with the shank passage 5 through which head 14 projects when the members are interlocked, and the second word being placed below said passage 5, as shown in Figure 6. When more than one

button element is desired to be interlocked with one shank member the tubular shank post 10 is made sufficiently long to accommodate the desired number of button elements. The button element or elements preceding the final button element to be so interlocked is pushed as closely to the shank base 11 as is possible. In so pushing the button element onto the tubular shank post 10 said arms 6 are not permitted to rest, even momentarily, in groove 18 but are made to pass that would be obstruction before the spring tension of said arms can operate said push button 12 to its forwardly position.

What I claim is:—

1. In a fastening device comprising a stud member in combination with a socket member having resilient jaws, said stud member comprising a stud-post having an attaching base and having a movable tip, said tip presenting a rearwardly facing abrupt shoulder, the free extremity of said stud-post being provided with cam surfaces adapted to meet the under-surface of said abrupt shoulder at an angle, and said movable tip, in close relation with said camming surfaces, providing an annular groove adapted to slightly catch said jaws upon the uniting of said members, and said camming surfaces, in co-operation with the closing tension of said jaws, being adapted to automatically precipitate said jaws forwardly against said abrupt shoulder thereby extendingly operating said tip and positively lodging said jaws behind said abrupt shoulder and interlocking said members.

2. A stud member having a proper attaching base and being adapted for an interlocking engagement with a socket member having resilient jaws, said stud member having an extendingly movable head presenting a rearwardly facing abrupt shoulder, the free extremity of said stud member being provided with camming surfaces adapted to meet the under-surface of said abrupt shoulder at an angle, and said movable head, in close relation with said camming surfaces, providing an annular groove adapted to slightly catch the resilient jaws upon the uniting of said members, and said camming surfaces, in co-operation with the closing tension of said jaws, being adapted to automatically precipitate said jaws forwardly against said abrupt shoulder thereby extendingly operating said head and positively lodging said jaws behind said abrupt shoulder of the extended movable head.

3. A fastening device comprising a stud member having a hollow stud-post; camming surfaces with which the free extremity of said stud-post is provided; an extendingly movable head having a rigid shaft mounted within said hollow stud-post, said head presenting a rearwardly facing abrupt shoulder, the under-surface of said

shoulder being adapted to meet said camming surfaces at an angle; and a socket member having resilient jaw means, the under-surface of said shoulder in close relation 5 with said camming surfaces providing an annular groove adapted to slightly catch said jaws upon the uniting of said members, and said camming surfaces, in co-operation with the closing tension of said jaws, being 10 adapted to automatically precipitate said jaws forwardly over said camming surfaces and against said abrupt shoulder thereby

extendingly operating said head and positively lodging said jaws behind said abrupt shoulder and interlocking said members; whereby said members may be separated only by the manual return of said head to said close relation to said camming surfaces thereby forcing said jaws backwardly over said camming surfaces and into 15 20 said annular groove from which they may be easily released over said head while said head remains under said manual control.

GEORGE HENRY ELWELL.
